POWDER DISPENSER

Application filed September 16, 1931. Serial No. 563,210.

This invention relates to powder dispensers of the type in which loose powder is ejected by the compressing action of a follower plate and movement of a perforate plate, and has 5 for its object to provide a simple and inexpensive device of this type which is convenient to operate.

It has previously been suggested that vanity cases of the above type might be made to 10 operate by movement of a hinged cover. However such prior suggestions have contemplated a discharge of powder as the cover is released or opened and this has the disadvantage that powder is discharged before the 15 same is ready to be wiped up by the puff, with the result that excess powder may be discharged which would be in danger of getting on the clothes of the user. In order to eliminate this disadvantage the present invention 20 contemplates the cover being opened independently of any powder discharge and such discharge of powder not beginning until after the cover has attained a wide open position.

Referring to the drawings Fig. 1 shows 25 one embodiment of this invention with the mirror exposing the contents of the cover.

Fig. 2 is a side view of the device shown in Fig. 1.

Fig. 3 is a view corresponding to Fig. 1 except that the mirror has been raised to expose 30 the perforate plate, parts of which have been broken away.

Fig. 4 is a top plan view of the follower plate and removable bottom portion, with 35 parts of the follower plate broken away.

Fig. 5 is a side view of the device of Fig. 4.

Fig. 6 is a section on the line 6a—6a of Fig. 1.

Fig. 7 is a detail of the mirror.

Fig. 8 shows the construction of the frame member which holds the perforate plate down against the action of the spring.

Fig. 9 shows the perforate plate and its actuating springs.

Fig. 10 is the powder container and its spaced outer walls or casing.

Fig. 11 is a detail showing the spring and latching lug for the removable bottom portion adjacent the hinge end of the dispenser.

Fig. 12 is a detail of the cover latching lug, its spring and actuating projection.

Fig. 13 shows the spring for the latching lug of Fig. 14 and

Fig. 14 shows the latching lug for the removable bottom portion at the end opposite the hinge end of the container.

The powder dispenser 10 of this invention is provided with a hinged cover 11 of the shape illustrated in which is fastened a frame 12 for holding whatever is desired within the recess 13, such as a puff or rouge or both, and the lipstick holder 14 pivoted at 15 to the frame 12. The pintle 16 secures the knuckles of the cover 11 mirror 17 plate holding frame and the main body of the powder container, said last two members being illustrated in Figs. 8 and 10 respectively. The knuckles 18 of the mirror 17 are located in the central portion of the pintle.

For retaining the cover in closed position the latching lug 20 shown in Figs. 1, 3 and 12 is spring actuated and provided with a projection 19 extending out of the dispenser outer walls or casing for releasing the lug 20 and opening the cover. An inwardly stamped projection 21 on the cover is engaged by the lug 20 for holding the cover in closed position.

A removable bottom portion 22 provides accessibility for the powder container 23 and enables such container to be refilled with powder in a convenient manner when necessary. The side walls of the powder container are shown quite clearly by the numeral 24 in Figs. 3 and 10. The perforate plate 25 closes one end portion of the container 23 and slides along the top of the container walls 24, preferably being guided by engagement with the inner sides of the outer casing walls 35. The perforations in the plate 25 are of the shape illustrated and the dotted line in Fig. 3 shows the relation between the plate perforations and the container walls 24.

The follower plate 26 presses the loose powder against the perforate plate by the action of the spring plate 27 having the arms or leaves 28 and 29 as illustrated in Figs. 4 and 5. This spring plate is secured to the removable bottom portion 22 by means of the bent over

projections 30 or in any other convenient manner. Since the yieldable latching lugs for retaining the removable bottom portion 22 are on the inside of the casing they engage the recesses 32 one at each end of the bottom portion 22. Said recesses 32 are formed between the main body portion 22 and the spring plate 27 which is raised or bent up from the main bottom portion 22 to form the recess and the stamped up sides for the bottom portion 22 constitute the sides of each recess 32. Since the powder container is of shallow depth the follower plate 26 and leaf springs 28 and 29 should also be compactly arranged. Therefore the springs are of only one thickness and not bent back on themselves. With such a construction it is necessary for sliding movement to take place between the end portions of the leaf springs and either the follower plate or the bottom portion 22. For convenience such sliding movement is arranged to take place adjacent the follower plate 26 by having the end portions of the leaf springs reduced in width as illustrated and inserted between stamped out strap portions 31 and the follower plate 26.

As shown in Fig. 6 a spring 33 is constructed to maintain the lipstick holder 14 in raised position whenever the cover is open and when closed the lipstick holder 14 is held within its recess illustrated. By having the outer end portion of the lipstick holder 14 raised whenever the cover is open it will be seen that the lipstick carrier 34 may be easily grasped and pulled out of the holder 14 for convenient use.

From Fig. 10 it may be seen that the outer casing or walls 35 of the dispenser are integrally connected by the bottom portion 37 with the inner or container walls 24, the same being made from a single stamping. At opposite end portions of the walls 24 are provided recesses 38 through which the latching lugs for the removable bottom portion 22 extend. Knuckles 39 are formed on the walls 35 for receiving the pintle 16.

In Fig. 11 is shown the latching lug 40 which projects through the recess 38 adjacent the hinge end of the container, said lug being integral with the spring portion 41 and the spacer portions 42. The spring 41 is normally contiguous the end wall 24 containing the recess 38 while the portions 42 lie against the bottom of the casing 37 and engage the outer end wall 35 below the knuckles 39 to space the ends of the spring 41 from the outer wall 35. The lug 40 is so shaped as to allow the removable bottom portion 22 to be snapped in position and the latching lug for the opposite end of the removable bottom 22 is of similar shape so that either end of the removable bottom will fit within either end of the container. As the removable bottom 22 is snapped in place the spring 41 is bent back sufficiently to with-

draw the lug far enough to allow it to engage and hold within the bottom recess 32, as shown the lug 40 is slightly rounded or wedge shaped for this purpose. The spring 47 and spacing portions 48 serve an analogous purpose at the opposite end of the container. At this end of the container the latching lug 45 on the member 43 fits into a recess 38 in the wall 24, not shown, but opposite the recess 38 in Fig. 10 which is shown.

The actuating member 43 for the latching lug 45 fits over a perforation shown in Fig. 3 with the projection 44 extending through said perforation so as to be engaged by the thumb or fingernail of the operator from outside of the dispenser and moved in a direction away from the hinge portion of the dispenser to bend the spring 47 and move the lug 45 far enough to release the removable bottom portion, at which time the springs 28 and 29 will raise the bottom portion 22 far enough to be grasped and pulled out. After refilling the container the removable bottom portion is snapped into position with the lugs 40 and 45 retaining each end thereof by engagement within the recesses 32. It will be understood that if desired the removable bottom portion 22 need not project below the plane of the bottom portion of the casing, instead of extending slightly below the same as shown in Fig. 2. As shown in Fig. 3 the projections 46 on the member 43 are placed between the end wall 24 and the spring 47.

The cover latching lug 20 is made integral with its spring 49 and provided with a projection 19 extending out of the dispenser casing as illustrated in Figs. 1, 2, 3 and 12, said projection passing through the hole 51 shown in Fig. 10. The spring 49 is stepped or notched as illustrated, the first stepped portion 52 serving to engage the spacer portions 48. The next step or notched portion 53 is received within the cooperative recesses 54 in the ends of the holding frame 55 so that the spring 49 serves to retain the end portion of the frame 55 remote from its knuckles 56. When the projection 19 is pressed inwardly so that the latching lug 20 releases the cover, the holding frame 55 is provided with a recessed portion 50 as shown in Figs. 1 and 8 to give clearance.

The perforations 57 in the plate 25 are of arcuate shape and are arranged in rows as illustrated. The lateral edges of the plate 25 are bent as shown at 59 to provide guide channels 58 for receiving the helical springs 60 and maintaining them in a substantial alignment or straight axial condition while under compression. The springs 60 are each secured at one end to the movable plate preferably by having the end of each channel 58 adjacent the hinge portion of the container closed, or if desired these springs 60 need not be secured to, but merely placed within the channels 58 so that they may exert a thrust

against the closed end of said channel. At the open end of the channels the springs project out from said channels and engage the front wall 35 of the outer casing as shown in Fig. 3. In order to maintain the projecting end portions of the springs in alignment with the rest of the springs it has been found desirable to place headed pins 61 within said springs so that the springs may engage the headed portion of said pins as shown in Fig. 3. Between the rows of perforations 57 is found a longitudinal rib or imperforate portion. While the contiguous powder surface below such imperforate portions of the plate 25 is not agitated, it has been found in practice that the powder beneath such portions 62 does not compact into an objectionable and substantially solid wall which might impede movement of the follower plate 26, because due to the arcuate shape of the perforations the particles of powder adjacent the plate 25 are given a slightly transverse movement at the same time the plate is moved longitudinally. This transverse movement of the powder is sufficient to break down any tendency for the powder to compact objectionably beneath the portions 62, with the result that a substantially free feed of powder is obtained until substantially all of it has been discharged.

The rear end of the plate 25 has a down turned flange 64 to which is secured an actuating lug 63 of substantially thicker metal than the flange. A portion of the end of the flange 64 is cut away as illustrated to receive the lug 63 and then the lug may be upset or headed over or riveted to the flange 64. This actuating lug 63 projects out through the hole 65 in the outer wall 35 as shown in Fig. 10. A stationary or fixed projection of a shape substantially the same as that portion of the lug 63 which projects out of the dispenser, is secured to the cover 11 as shown in Fig. 2. These portions 63 and 66 are slightly rounded on their edges where they engage. On opening the dispenser the cover may be moved almost 180 degrees to the position illustrated in Fig. 2 before any discharge of powder begins and before the projection 66 engages the lug 63. On continued opening of the cover it may be moved through a position slightly more than 180 degrees of opening and until the outer edge of the cover engages the outer edge of the dispenser main body portion. In this last position the lug 63 will have been forced entirely within the dispenser by the projection 66 and said projection 66 will extend through the hole 65 and into the space between the inner and the outer walls 24 and 35. In this last position of the cover when it has a maximum opening, projection 66 moves lug 63 and the plate 25 forwardly further compressing the spring 60. On partially closing the cover the springs 60 move the plate 25 in the opposite direction until the lug 63 projects

out of the dispenser and until the flange 64 of the plate engages the rear outer wall 35 below the knuckles 39.

To assemble the various parts of the dispenser the spring lug of Fig. 11 may be first inserted in place at the hinge end of the container. The lug actuating member of Fig. 14 is put in place over its perforation at the opposite end of the dispenser. The spring 47 of Fig. 13 is next put in place as previously described and is illustrated in Fig. 3. The cover latch spring of Fig. 12 is then positioned with its projection 19 extending out of the hole 51 and with care being taken to see that the step portion 52 engages the spacing members 48 of the spring 47. The plate 25 is next positioned by first inserting the lug 63 through the hole 65 and then compressing the springs 60 until the plate has been lowered into contact with the top edges of the walls 24 with the springs and pins engaging the inner front portion of the wall 35 as shown in Fig. 3. In order to more firmly hold the plate 25 down on top of the walls 24 against the action of the follower plate springs, the frame 55 is put in position with its front edge recesses 54 engaging the cooperative portions 53 of the spring 49, after which the pintle receiving knuckles 56 may be lowered into place. The mirror is then put in position and finally the cover portion 11, after which the pintle 16 may be passed through the knuckles of the several members to hold the parts together. Subsequently the container may be inverted and powder placed into the container 23 from the rear or bottom side, after which the bottom portion 22 may be snapped in place. If desired a puff may be arranged to fit within the frame 55 and rest on top of the plate 25 so that such puff may be held in place by the mirror when the cover is closed and serve as a guard against discharge of any excess of loose powder through the plate perforation during the filling operation and before the powder has been compacted by the follower plate.

As is well known in the art after the loose powder has been compacted by a follower plate there is little likelihood of an undesirable excess being discharged through the perforations of a movable plate even when such plate does not have its perforations closed by a shutter as was the custom in the old Norida vanity case of Soyez 1,504,001.

Among the advantages of this invention may be mentioned the discharge of powder does not take place in response to any movement of the cover until well after the cover has been opened widely. This precludes the discharge of powder during the initial opening movement of the cover to thus guard against the presence of an undesirable excess of powder. The cover may be held in one hand and the main body portion of the dis-

dispenser in the other hand during continued opening movement from the position illustrated in Fig. 2 for discharge of powder, after which the powder discharged upon the 65 top of the movable plate 25 may be wiped up by a puff. If desired the likelihood of any loose powder being blown over the user's clothes may be further minimized by holding the cover 11 in one hand and with the puff in 70 the other hand pressing the puff and wiping it over the surface of the plate 25 at which time the pressing movement causes the plate 25 to be moved longitudinally due to relative 75 pivotal movement between the cover 11 and main body portion 10 of the dispenser. Previous attempts to manually actuate a perforate plate of a vanity case in one direction and then have the plate moved in the opposite direction by means of a leaf spring 80 have not been successful. The powder seems to compact into an almost solid mass and a leaf spring to be successful in all parts of the plate travel would have to be excessively long in order to provide the necessary 85 strength to force the plate against the compacted powder within its perforations and throughout its entire travel.

Vanity cases in order to be attractive must be compactly designed to occupy a minimum 90 space within a lady's handbag. Investigations by us have shown that leaf springs for operating the movable perforate plate in one direction are not practicable. It has been discovered that a plurality of helical springs 95 especially if placed under compression may be made to give the requisite force necessary throughout the full plate travel. Features of the present invention include the provision of guide channels and pins for such 100 springs to maintain them in desirable alignment for best operation. The recesses 105 when formed between the bottom 22 and the spring member 27 may be placed close to the outer surface of the bottom 22 and at the 110 same time have such bottom portion compactly constructed to be of minimum depth. The removable bottom portion 22 has either of its ends interchangeable to engage the latching lugs 40 and 45. The lipstick holder 115 is automatically raised on opening the cover to facilitate withdrawal of the lipstick carrier. The engagement between the cover latching lug spring and the holding frame 120 insures a secure fastening for the front 125 end of said frame at all times. The only operative connection between the cover and movable plate are the lug 63 and projection 130 66 which occupy only a small amount of space on the outside of the dispenser and 60 are not objectionable.

We claim:

1. A powder dispenser comprising a container for loose powder, a perforate plate across one end portion of said container, a 65 follower plate within said container, means

whereby loose powder within said container may be compressed between said follower plate and perforate plate, a hinged cover for said dispenser, and means for actuating said perforate plate in response to movement of 70 said cover during its motion when well opened without actuating said plate during the early opening movement of the cover, the perforate plate being adapted to discharge powder on movement in either direction. 75

2. A powder dispenser comprising a container for loose powder, a perforate plate across one end portion of said container, a follower plate within said container, means 80 whereby loose powder within said container may be compressed between said follower plate and perforate plate, a hinged cover for said dispenser, and means for actuating said perforate plate in response to movement of 85 said cover during its motion when well opened, said cover being movable through any acute angle during opening from its closed position without causing any actuation of said perforate plate. 90

3. A powder dispenser comprising a container for loose powder, a perforate plate across one end portion of said container, a follower plate within said container, means 95 whereby loose powder within said container may be compressed between said follower plate and perforate plate, a hinged cover for said dispenser, and means for actuating said perforate plate in response to movement 100 of said cover, said plate actuating means including a projection extending out of the dispenser adjacent the cover hinge in a direction away from said perforate plate, said projection being of a length such that the cover engages said projection only after it 105 has moved through a substantial angular distance from its closed position and not before. 110

4. A powder dispenser comprising a container for loose powder, a perforate plate across one end portion of said container, a follower plate within said container, means whereby loose powder within said container may be compressed between said follower plate and perforate plate, a hinged cover for 115 said dispenser, and means for actuating said perforate plate in response to movement of said cover, said plate actuating means including a projection extending out of the dispenser adjacent the cover hinge in a direction away from said perforate plate, and a 120 projection on said cover adapted to engage the first mentioned projection and actuate said perforate plate only after the cover has been moved through about 180 degrees. 125

5. A powder dispenser comprising a container for loose powder, a perforate plate across one end portion of said container, a follower plate within said container, means whereby loose powder within said container 130 may be compressed between said follower

- plate and perforate plate, manual means for moving said perforate plate in one direction and spring means for moving said plate in the opposite direction, said spring means comprising at least two helical springs extending in the general direction of perforate plate travel and of a length at least about as long as the longest dimension of the powder container, said springs being located in guide spaces on opposite sides of the container between the container side walls and outer side walls of the dispenser.
6. A powder dispenser comprising a container for loose powder, a perforate plate across one end portion of said container, a follower plate within said container, means whereby loose powder within said container may be compressed between said follower plate and perforate plate, and means for actuating said perforate plate to discharge powder from the container, the perforations in said plate being arranged in rows with a plurality of longitudinal ribs or imperforate plate portions between said rows whereby the powder in said container and under said imperforate longitudinal plate portions is not passed over by any plate perforations, and said plate perforations being so shaped as to move the powder in both directions transversely with respect to the portions of the powder which are not passed over by any plate perforations.
7. A powder dispenser comprising a container for loose powder, a perforate plate across one end portion of said container, a follower plate within said container, means whereby loose powder within said container may be compressed between said follower plate and perforate plate, a hinged cover for said dispenser, and means for actuating said perforate plate in response to movement of said cover, said cover being movable through a substantial portion of its travel toward and from a closed position without movement of said perforate plate, the resistance to plate movement offered by the powder being substantially the same for plate movement in either direction.
8. A powder dispenser comprising a container for loose powder, a perforate plate across one end portion of said container, a follower plate within said container, means whereby loose powder within said container may be compressed between said follower plate and perforate plate, a latch for said cover means extending out of the container for actuating said latch, and means extending out of the container on the side opposite said latch for actuating said perforate plate.
9. A powder dispenser comprising a container for loose powder, a perforate plate across one end portion of said container, a follower plate within said container, means whereby loose powder within said container may be compressed between said follower
- plate and perforate plate, a hinged cover for said dispenser, and means for actuating said perforate plate in response to movement of said cover, said plate actuating means comprising a knob extending out of the dispenser and of a size adapted to be engaged by a knob carried by the cover and pushed within the dispenser by said knob on the cover.
10. A powder dispenser comprising a container for loose powder, a perforate plate across one end portion of said container, a follower plate within said container, means whereby loose powder within said container may be compressed between said follower plate and perforate plate, the perforations in said plate being of arcuate shape and arranged in rows.
11. A powder dispenser comprising a container for loose powder, a perforate plate across one end portion of said container, a follower plate within said container, means whereby loose powder within said container may be compressed between said follower plate and perforate plate, a hinged cover for said dispenser, and means for actuating said perforate plate, and means tending to equalize compression on the powder and tending to equalize the feed of powder through the various plate perforations, which last mentioned means comprises a plurality of leaf springs symmetrically located for pressing the follower plate substantially uniformly against the powder at each end portion of the container.
12. A powder dispenser comprising a container for loose powder, a perforate plate across one end portion of said container, a follower plate within said container, means whereby loose powder within said container may be compressed between said follower plate and perforate plate, a movable bottom portion for filling the container, said powder compression means including a leaf spring between said follower plate and movable bottom portion, the container being shaped to guide said follower plate in a direction substantially normal to the movable bottom portion and the ends of said spring being engaged by the follower plate and movable bottom portion and fixed at one end while slideable at the other in such manner that movement of the follower plate in the container causes a transverse sliding movement of the slideable end of said spring.
13. A powder dispenser comprising a container for loose powder, a perforate plate across one end portion of said container, a follower plate within said container, means whereby loose powder within said container may be compressed between said follower plate and perforate plate, a movable bottom portion for refilling the container, said powder compression means including a leaf spring between said follower plate and movable bottom portion, an outer casing around said container.

tainer, an integral portion of said spring being fixed contiguous said movable bottom portion, there being a small recess formed between said spring and bottom portion 5 of a size adapted to receive a yieldable latching projection within said recess whereby said latching projection may be on the inside but adjacent the dispenser outer casing.

14. A powder dispenser comprising a container for loose powder, a perforate plate across one end portion of said container, a follower plate within said container, means whereby loose powder within said container may be compressed between said follower plate and perforate plate, a bottom portion removable for refilling said container, yieldable latching lugs arranged to engage opposite sides of said removable bottom portion whereby said bottom portion may have either 15 of its lug receiving end portions engage either latching lug, and at least one of said lugs being actuated for removing said bottom portion.

15. A powder dispenser comprising a container for loose powder, a perforate plate across one end portion of said container, a follower plate within said container, means whereby loose powder within said container may be compressed between said follower plate and perforate plate, a hinged cover for said dispenser, and means for actuating said perforate plate, a frame member for holding said perforate plate in position against the thrust of said powder compressing means, a latching member for releasing said cover, a spring cooperating with said latching member for maintaining the same in a position to hold the cover closed, said latch spring being shaped to engage and retain said holding frame member at one end portion thereof.

16. A powder dispenser comprising a container for loose powder, a perforate plate across one end portion of said container, a follower plate within said container, means whereby loose powder within said container may be compressed between said follower plate and perforate plate, manual means for moving said perforate plate in one direction and spring means for moving said plate in the opposite direction, said spring means comprising at least two helical springs extending in the general direction of perforate plate travel and of a length at least about as long as longest dimension of the powder container, said springs being located in guide spaces on opposite sides of the container between the container side walls and outer side walls of the dispenser, said guide spaces being constituted by channels secured to and extending along the sides of said perforate plate, and a pin axially within each spring and extending from within said guide channels out thereof at one end to engage a dispenser wall.

17. A powder dispenser comprising a container for loose powder, a perforate plate

across one end portion of said container, a follower plate within said container, means whereby loose powder within said container may be compressed between said follower plate and perforate plate, manually operable means for moving said perforate plate in one direction and spring means for moving said plate in the opposite direction, said spring means comprising a helical spring held under compression and engaging said perforate plate at one end portion and a stationary portion of the dispenser at the other end, said spring being arranged with a guide housing to maintain the spring portions in operative position.

18. A powder dispenser comprising a container for loose powder, a perforate plate across one end portion of said container, a follower plate within said container, means whereby loose powder within said container may be compressed between said follower plate and perforate plate, a lug extending out of the dispenser for actuating said perforate plate from outside said dispenser, said lug being of much thicker material than said plate and riveted to a portion of said plate out of the plane of the plate.

19. A powder dispenser comprising a container for loose powder, a perforate plate across one end portion of said container, a follower plate within said container, means whereby loose powder within said container may be compressed between said follower plate and perforate plate, a hinged cover for said dispenser, and means for actuating said perforate plate in response to movement of a puff wiped over the perforate plate under pressure with one hand while said cover is held in the other hand, the opening movement of said cover being independent of any perforate plate movement to discharge powder.

20. A powder dispenser comprising a container for loose powder, a perforate plate across one end portion of said container, a follower plate within said container, means whereby loose powder within said container may be compressed between said follower plate and perforate plate, a hinged cover for said dispenser, and means for actuating said perforate plate in one direction in response to movement of said cover, and a plural helical compression spring means for actuating said cover in a direction opposite to the movement of said plate under influence of said cover, said first mentioned plate actuating means being independent of the opening movement of the cover during at least about the first quadrant of its opening movement.

21. A vanity case of the compressed loose powder type having a cover and a perforate plate through which loose powder is discharged, operating connections between said cover and perforate plate and located entirely on the outside of said vanity case for

enabling loose powder to be discharged through said perforations in response to movement of said cover.

22. A powder dispenser comprising a container for loose powder, a single perforate plate across one end portion of said container, a follower plate within said container, means whereby loose powder within said container may be compressed between said follower plate and perforate plate, at least a portion of the perforate portion of said plate being always open and said powder compressing means being the only means for preventing the leakage of powder through said perforate plate in the absence of any shutter mechanism or second perforate plate for said perforate portion of said plate, the perforate portion of said plate and its travel being so related that less than the entire powder surface contiguous the perforate plate is shaved off at each stroke of said plate, the perforate portion of the plate adjacent the unagitated or unshaved part of the powder surface being arranged to move some of the powder transversely to the direction of plate travel whereby any tendency for the powder to compact into an almost solid and more dense mass is substantially reduced and the free feed of powder through the plate perforations is unimpeded.

23. A vanity case comprising a casing, a container for loose powder within the casing, a recessed plate sliding relative to said container, a projection extending outside said casing, and a cover pivoted to the casing above said projection and adapted to engage said projection when the cover is moved while wide open and to directly produce said relative sliding movement between the plate and container.

24. A vanity case of the loose powder type comprising a powder container, a pivotal cover, a recessed plate, means for producing relative movement between said plate and container for discharging powder to be wiped up by a puff, said means including the cover, the resistance offered by the powder to said relative movement between the plate and the container being substantially the same in each direction of said movement, and the discharge of powder being substantially free and without clogging of the powder in the container.

25. A vanity case of the loose powder type comprising a powder container, a recessed plate across the discharge side of said container, mechanism for producing relative movement between said plate and container for discharge of powder to be wiped up by a puff, said mechanism including an elongated helical spring continually under stress and cooperating with said plate and container for effecting said relative movement in one direction whereby the actuating force for said movement may be substantially uniform

throughout a large amplitude of movement, a housing for said spring, and means for effecting said movement against the action of said spring, said means including a pivotal member movable through a wide angle from a position adjacent said container, the powder in said container being normally in contact with said plate while the vanity case is in its position for the discharge and wiping up of powder and said discharge of powder being substantially free from clogging within said container.

In witness whereof we have hereunto set our hands this 15th day of September, 1931.

NATHAN KASDAN.

RICHARD F. LANDWEHR.

DANIEL POLLACK.
